CLAIM

The ornamental design for an automobile, as shown and described.

DESCRIPTION

FIG. 1 is a front perspective view of an automobile showing our new design;

FIG. 2 is a front elevational view thereof;

FIG. 3 is a right side elevational view thereof, the left side being a mirror image;

FIG. 4 is a rear perspective view thereof; and,

FIG. 5 is a rear elevational view thereof.

The portions of the vehicle and wheels shown in broken lines are for illustrative and environmental purposes and form no part of the claimed design.
